UNITED STATES PATENT OFFICE.

FREEMAN E. COLLIER, OF MINNEAPOLIS, MINNESOTA, ASSIGNOR TO FOLEY SAW TOOL COMPANY, INCORPORATED, OF MINNEAPOLIS, MINNESOTA, A CORPORATION OF MINNESOTA.

SAW-FILING MACHINE.

Application filed March 19, 1927. Serial No. 176,659.

My invention relates to saw filing machines and is in the nature of an improvement or refinement of the saw filing machine disclosed and broadly claimed in the 5 Hugh B. Foley United States Letters Patent 1,224,293 issued of date May 1, 1917, and his pending application filed August 13, 1925 under Serial No. 50,066.

Generally stated, the invention consists 10 of the novel devices and combinations of devices hereinafter described and defined in the claims.

In the accompanying drawings, which illustrate the invention, like characters indicate like parts throughout the several views.

Referring to the drawings:

Fig. 1 is a front elevation of the improved saw filing machine in which is mounted a hand saw for filing;

20 Fig. 2 is a right side elevation of the machine and showing the saw in section;

Fig. 3 is a left side elevation of the machine and showing the saw in section;

25 Fig. 4 is a horizontal section taken on the line 4-4 of Fig. 2;

Fig. 5 is a detail view principally in section taken on the irregular line 5-5 of Fig. 4;

30 Fig. 6 is a view principally in transverse vertical section taken on the line 6-6 of Fig. 2;

Fig. 7 is a transverse vertical section taken on the line 7-7 of Fig. 3;

35 Fig. 8 is a detail view with some parts sectioned on the line 8-8 of Fig. 3, on an enlarged scale;

Fig. 9 is a fragmentary detail view in section taken on the line 9-9 of Fig. 8, on an enlarged scale;

40 Fig. 10 is a detail view with some parts sectioned on the line 10-10 of Fig. 2, on an enlarged scale;

Fig. 11 is a fragmentary detail view with some parts sectioned on the line 11-11 of Fig. 10, on an enlarged scale;

45 Fig. 12 is a fragmentary view in front elevation with some parts sectioned on the line 12-12 of Fig. 2, on an enlarged scale, with certain of the parts in different positions from that shown in Fig. 1;

50 Fig. 13 is a detail view principally in section taken on the line 13-13 of Fig. 12;

Fig. 14 is a front elevation of the improved saw filing machine having a circular saw mounted therein for filing; 55

Fig. 15 is a fragmentary right side elevation of the machine, as shown in Fig. 14; and

Fig. 16 is a fragmentary detail view with some parts sectioned on the line 16-16 of Fig. 14.

To illustrate the manner in which a hand saw, bucksaw, back saw, meat saw or the like is held in the machine and sharpened or new teeth cut thereon, there is illustrated 65 in Figs. 1, 2, 3, and 12 a hand saw *a*. In Figs. 14, 15, and 16 there is illustrated in the machine a circle saw *b*, positioned for filing.

The numeral 20 indicates a flat horizontal base plate bolted to a bench *c* and having at its front edge a downturned flange 21 which overlaps and engages the respective edge of said bench to assist in holding said base plate 20 properly positioned 70 thereon. An upright face plate 22 is detachably secured by bolts 23 to the flange 21 and extends both above and below the base 20. The heads of the bolts 23 are set into recesses in the face plate 22 so as not 75 to obstruct said face plate (see Fig. 1).

Formed in the face plate 22, above the base 20, is a large opening 24, and a long vertical slot 25 is formed in said face plate below the opening 24 and at the transverse 80 center of said face plate. The base 20 and flange 21 are bifurcated at 26, for a purpose that will presently appear.

An upright vice member 27 has its lower end hinged at 28 to and between a pair of hinge lugs on a forwardly projecting lug 29 on the lower end of the face plate 22. On the upper end of the vice member 27 is an upwardly and inwardly curved jaw 30. Co-operating with the jaw 30 is a correspondingly formed fixed jaw 31 integrally formed with the face plate 22 at the bottom of the opening 24. 90

The vice member 27 is operated to adjust the jaw 30 toward the jaw 31 or release the same and is held where set by a two-part clamping bolt and co-operating nut-acting member. Said bolt comprises a head member 32 inserted through the slot 25 from the 95

back of the face plate 22 with its head impinging thereagainst and a tubular member 33 which extends through a vertical slot 34 in said vice member coincident with the slot 25 and has internal threaded engagement with said head member. On the outer end of the bolt member 32 is a hand wheel 35 by which said bolt member may be turned on the bolt member 32. Said bolt member 32 has shouldered engagement with the face plate 22 to prevent the same from turning in the slot 25. The nut-acting member 36 has threaded engagement with the tubular bolt member 33 and impinges against the face of the vice member 27 as a base of resistance, and has on its outer end a hand wheel 37 by which it may be turned. Obviously, by tightening the nut-acting member 36 on the bolt member 33, the jaw 30 may be adjusted toward the jaw 31.

Usually, an ordinary three-sided file *d* will be used to sharpen the teeth of a saw or cut new teeth therein and this file is arranged to be carried and given an endwise up and down movement by a crosshead guide that is mounted for angular adjustment in respect to the saw, the face plate 22, and base 20. The crosshead guide, as shown, is in the form of an upright plate 38 having at the upper portion of its front end a forwardly projecting arm 39 that is pivotally attached by a machine screw or stud 40 to a lug on the upper end of the face plate 22. It is important to note that the axis of the stud 40 is at the transverse center of the saw *a* and midway between the sides of the jaws 30 and 31. Formed with the bottom of the crosshead plate 38 are front and rear bearing lugs 41 which rest on planed segmental surfaces 42 on the base 20 and slidably support said plate. To hold the crosshead plate 38 where set, the same is secured to the base 20 by means of front and rear nut-equipped headed bolts 43 that are inserted upward through segmental slots 44 in said base and bores in the lugs 41 (see Figs. 4 and 5). Said slots 44 are formed in the planed surfaces 42 and on arcs of circles having their centers at the axis of the studs 40. The base plate 20, along the outer slot 44, is graduated at *e* to indicate the angle at which the crosshead guide 38 and hence the file *d* will be set in respect to the saw or in respect to a position at right angles to the saw.

Rigidly secured to the crosshead guide 38 at the upper and lower edges thereof, but laterally spaced therefrom, is a pair of parallel vertical guide rods 45. Mounted on these rods 45 for slight vertical movement is a secondary crosshead guide 46 having upper and lower ways in which a plate-like crosshead 47 is mounted for horizontal slid-

ing movement. This crosshead 47 is provided with a forwardly projecting file-carrying arm 48 equipped with longitudinally spaced depending file holders.

These file holders, as best shown in Figs. 8, 9, 10 and 11, include downwardly sprung-pressed plungers 49 that are seated in sleeve-like portions 50 of the arm 48 and are provided at their upper ends with thumb nuts 51 by means of which they are made vertically adjustable. The plungers 49, at their lower ends, are formed with sleeve-like heads 52 and 53. Double-ended endwise reversible sleeve-like sockets 54 and 55 are inserted axially through the heads 52 and 53. When the thumb nuts 51 are loosened, the plungers 49 will be pressed downward by their springs and thumb screws 56 are provided for securing said plungers to the sleeve-like portions 50 of the arm 48 in different adjustments.

The inner plunger 49 and its head 52 are longitudinally slit so that when said plunger is engaged by the respective screw 56, said head will be contracted onto the sleeve-like socket 54 and secure the same where set. The head 53 is longitudinally slit and provided with a thumb screw 57 for contracting said stud onto the socket 55 and hold the same where set. The passage through the sleeve-like socket 54 is triangular in cross section, as shown in Fig. 8, to receive the outer end portion of the file *d*. Said passage at the two ends of the sleeve-like socket, is of a different size in cross section to hold files of different sizes.

The passage through the sleeve-like socket 55 is round and adapted to receive the shank of the file *d*, and the diameter of said passage, at the two ends of said socket, is different so as to receive different sized shanks. Obviously, the sleeve-like sockets 54 and 55 hold the file *d* horizontally, and by manipulating the nuts 51 said file may be raised or lowered, and by turning the sockets 54 and 55 in their heads said file may be transversely angularly adjusted.

The numeral 58 indicates a short shaft journaled in the angularly adjustable crosshead guide plate 38 and provided at its outer end with a spur gear 59 which meshes with a spur pinion 60 journaled on a stud 61 on said plate. On the hub of the pinion 60 is a half clutch 62 arranged to interlock with a half clutch 63 on the hub of a fly wheel 64 journaled on the stud 61. The fly wheel 64, as shown, is provided with a crank handle 65 by which it may be rotated by hand when the machine is to be hand-operated.

When the machine is to be operated by a motor, as illustrated in Figs. 1, 2, 14 and 15, an electric motor 66 is bolted to a bed plate 67 which, in turn, is bolted to the top of the crosshead plate 38. On the armature shaft

of the motor 66 is a pulley 68 over which and the fly wheel 64 runs a belt 69 for driving said fly wheel from the motor 66.

At the inner side of the crosshead guide 5 plate 38, the shaft 58 is provided with a cam 70 and with a laterally offset crank arm 71. The secondary crosshead guide 46 is provided with an upper bearing lug 72, the flat under surface of which rests upon the cam 70. Said secondary crosshead guide 46 is also provided with a lower bearing lug 73, the flat upper surface of which is arranged to be engaged by the cam 70 when it is low. The purpose of this lug is to positively move 15 the secondary crosshead guide 46 to its low position. The numeral 74 indicates a roller-equipped screw that is adapted to be secured to the crank arm 71 in different positions from its axis to vary the throw of said arm 20 and works in a vertical cam slot 75 in the crosshead 47.

With the construction described, when the shaft 58 is rotated, the crank arm 71 will cause the crosshead 47, which carries the file 25 *d*, to reciprocate horizontally and the cam 70 will cause the secondary crosshead guide 46 and hence the crosshead 47 to move vertically. The timing of said movements is such that, at the limit of the outward movement of 30 the file *d*, the high portion of the cam 70 will come into action on the lug 72 and will lift the crosshead 47 and the file so that the file will be carried clear of the saw on its return movement, and when said crosshead 47 35 and the file have reached approximately the limit of the return movement, the lower portion of said cam 70 will come into action on the lug 72 and will allow the crosshead 47 and the file to drop to low position so that the file will properly come into action on the teeth of the saw. During the movement of 40 the crosshead 47 to low position the high part of the cam 70 will come into action on the lug 73 and positively move said crosshead.

45 The step by step feed movement of the saw is automatically produced by means best shown in Figs. 1, 12 and 14, and comprises as follows: Pivoted to the face plate 22 is a pair of reversely-acting bell-crank-shaped levers 76 which, at their opposing upper ends, are provided with reversely oblique screws 77 that afford adjustable contacts and that are engageable with a tappet plate 78 detachably secured by a screw 79 on an arm 50 80 that projects from the front upper portion of the secondary crosshead guide 46. The screws 77 are provided with lock nuts 81 that impinge against the levers 76 and hold said screws where set. Coil springs 82, anchored to the face plate 22 are attached to the opposing upper ends of the levers 76, tend to 55 60 65 yieldingly hold said arms with the screws 77 in contact with the tappet plate 78, as best shown in Fig. 12.

65 Reversely-acting driving dogs 83 (see

Figs. 1, 12 and 14) are pivoted to the lower ends of the levers 76 and are adapted to engage the teeth of the saw. At their outer ends, the dogs 83 are beveled to afford flat stop surfaces 84, and the lower arms of said 70 levers 76 are provided with spring-pressed plungers 85 formed with heads against which either the flat surfaces 84 of the dogs 83 or the backs thereof are arranged to engage. When the dogs are turned up, their backs 75 will be engaged by the spring-pressed plungers 85 and will be yieldingly held in inoperative position, as shown at the right in Figs. 1, 12 and 14. But when the dogs 83 are turned down, the heads of the spring- 80 85 pressed plungers 85 will engage the surfaces 84 of said dogs and yieldingly hold said dogs in position for action on the saw teeth, as shown at the left in Figs. 1, 12 and 14.

The numeral 86 indicates stop screws adjustably applied to lugs on the opposite edges of the face plate 22 and which limit the outward or return movements of the levers 76 against the action of the springs 82. These stop screws 86 are provided with lock nuts 86' which impinge against the lug with which said screws have threaded engagement. The feeding device described will feed a saw in either direction, but of course, only one dog 83 will be operated at any one time. In 90 95 the adjustment shown in Fig. 1, the saw will be fed from the left to the right.

When the crosshead 47 and the file have reached approximately the limit of their outward movement, said plate, and hence the secondary crosshead guide 46, will be raised by the cam 70 and the upward movement then imparted to the arm 80 will cause its tappet plate 78, operating on the screws 77, to impart operative movements to the levers 76 and operative movement to the dog 83 that is turned down to operative position, thereby positively producing the saw-feeding movement. When at approximately the limit of the return movement of the crosshead 47, the secondary crosshead guide 46 and arm 80 are lowered and the springs 82 will impart the return movements to the levers 76 and the operative dog 83. Of course, there will be no feeding movement produced 110 115 during the time that the file is performing its outward or saw filing movement.

When the saw has been positioned, the driving dog 83 may be properly set thereto and by adjustment of the co-operating stop screw 86. With the stop screw 86 set in any particular position, the amount of movement that will be given to the operative dog 83 will be determined by the adjustment of the co-operating screw 77 in respect to the bearing plate 78. In Fig. 12 the bearing plate 78, as shown, is just moved into contact with the screws 77 and hence just ready to cause the dog-feeding movement as said plate is moved upward.

To support the guide saw *a* or similar saw blades there is provided a pair of clamping bars 87 having at their ends, nut-equipped bolts 88 for clamping said bars against the 5 opposing sides of a saw blade parallel to the saw teeth (see Fig. 1).

The inner clamping bar 87 is supported on a pair of horizontally spaced angle brackets 89 on the face plate 22, and the outer clamping bar 87 is supported on an angle bracket 90 on the vice member 27. A pair of horizontally spaced upper angle brackets 91 on the face plate 22 overlie the inner clamping bar 87 and prevent the same from lifting 15 from the angle brackets 89. The brackets 89, 90 and 91 hold the clamping bars 87 and hence the saw for straight line endwise movement, but permit limited angular movement of said clamping bars and saw. The 20 clamping bars 87 work just under the jaws 30 and 31 with the toothed upper edge portion of the saw extending above said clamping bars and between the jaws 30 and 31. The adjustment of the jaw 30 in respect to 25 the jaws 31 is such that the saw can just move between said jaws and is held thereto against angular movement, and at which point the file acts on one of the teeth just above said jaws.

30 Heretofore, saw-feeding action in saw filing machines has been produced by action on the old or dull teeth, and to cut new teeth on a saw blade it has been necessary to clamp the same between toothed bars to which the 35 feeding action is imparted. The result of filing a saw to which the feeding action is produced on the old or dull teeth is that the teeth will be irregularly spaced and the file will not be properly positioned between the 40 teeth so that the filing action on the teeth will leave the same uneven.

One of the primary objects of my present invention is to overcome this deficiency in saw filing machines by feeding a saw blade from the last filed tooth so that the teeth will be accurately spaced and if there are any irregularly spaced teeth in the saw blade, they will be corrected. To cut new teeth on a saw blade it is only necessary to 45 file the first tooth and then set the feeding device to start its feeding action from this tooth. In carrying out this part of the invention, I provide a guide cam arm 92 arranged to be engaged by cam pins 93 which 50 extend transversely through the dogs 83. This guide cam arm 92 is detachably and 55 adjustably attached to the face plate 22 by a nut-equipped bolt 94 which extends through a longitudinal slot 95 in said arm and frictionally clamps said arm against the face plate 22.

When filing hand saws or the like, the guide cam arm 92 will be attached to the left-hand side of the face plate 22 so as to 60 feed said saw from the left to the right (see

Fig. 12). When filing a band saw, the guide cam arm 92 will be reversed and shifted to the right-hand side of the face plate 22 and its bolt 94 passed through a hole 96 in said face plate. When filing a circle saw, the bolt 94 will be passed through a hole 97 just below the hole 96. The guide cam arm 92 is arranged to hold the operative dog 83 raised by means of its cam pin 93 and out of contact with the old or dull teeth during the projecting and retracting movement of said dog and then allow the same to drop by gravity during its projecting movement into engagement with the last filed tooth and impart a step of movement to the saw blade during the lifting of the file from the saw, and which movement corresponds to the spacing of the teeth on the saw blade.

It may be here stated that the adjustment of the jaw 30 in respect to the jaw 31 is such as to place sufficient drag on a saw mounted therebetween to cause the saw blade to partake only of the actual movement imparted thereto by the dog 83. During the lowering movement of the file, the dog 83 will be lifted from the engaged tooth by the cam pin 93 and carried over the old or dull teeth and supported out of contact therewith, as indicated by broken lines in Fig. 12. By 95 endwise adjusting the guide cam arm 92 the same may be set for spacing a predetermined number of teeth per inch, depending upon the saw being filed, or by raising or lowering the inner end of the guide cam arm 92, the dog 83 may be positioned to drop by 100 gravity to the bottoms of the teeth being filed.

To hold a circle saw *b*, with freedom to be turned about its axis for filing, there is mounted on the bolt member 32 a combined clamping and centering device. This device comprises a cup-shaped member 98 which bears against the face plate 22 and a conical member 99 extending into said cup-shaped member 98 which bears against the face plate 22 and a conical member 99 extending into said cup-shaped member. Said members 98 and 99 are provided with axial openings through which the bolt member 32 loosely extends. To mount the circle saw *b* in the machine for filing, the bolt members 32-33 are separated and the bolt member 32 inserted through the eye of said saw. The conical member 99 is then applied to the bolt member 32 and inserted through the eye of the saw *b*, as best shown in Fig. 16. The blade member 32 is then applied to the conical member 99, forces the same into the eye of the saw and frictionally clamps said saw between the rim of the members 98 and 99.

With the saw *b* thus mounted, the same extends between the jaws 30 and 31 and is frictionally held thereby for rotation under 130

pressure to produce step by step saw-feeding action by one of the dogs 83. To sharpen a circle saw after the same is mounted in the machine, as just described, the guide cam 5 arm 92 is reversed and shifted to the left side of the face plate 22, as previously stated, and the left-hand dog 83 is turned into an inoperative position and the right-hand dog is turned down for action on the 10 teeth of the circle saw. The operation of the machine in sharpening a circle saw and the feeding action thereof is the same as that for sharpening the hand saw with the exception that the feeding action of the saw is 15 from the right to the left.

To raise or lower the two-part bolt 32-33 and the combined centering and clamping device 98-99 and hold the same with the saw properly centered in respect to the file, 20 there is provided a long upright screw 100, the upper end of which is swivelled in the flange of the member 98 and the intermediate portion thereof extends loosely through a bore in the lug 29 and is provided 25 with a nut 101 which rests on said lug and is held from turning by the face plate 22. On the lower end of the screw 100 is a hand wheel 102 by which said rod may be turned in the nut 101 to raise or lower the member 98 and hence the parts carried thereby (see 30 Fig. 16).

When the machine is used to file band saws, the saw is fed through the machine from the right to the left, and the pivot for 35 the right-hand lever 76 is shifted into a hole 103 in the face plate 22 in order to properly position the respective dog 83.

40 Springs 104, anchored to the crosshead guide 38 and attached to the secondary crosshead guide 46, are under strain to hold said guide 46 in its low position.

What I claim is:

45 1. In a saw filing machine, a file holder, means for imparting saw filing movement to the file holder, a saw-feeding dog, means for causing the dog to engage the last filed

tooth, and means for operating the dog to cause the same to move the saw and position the last filed tooth a predetermined distance beyond the position in which it was filed. 50

2. The structure defined in claim 1 in further combination with adjustable means for varying the distance in which the last filed tooth may be positioned beyond said filing position. 55

3. In a saw filing machine, a file holder, means for imparting saw filing movement to the file holder, a saw-feeding dog, means for causing the dog to engage the last filed tooth, a guide cam arm arranged to cause the dog to engage the last filed tooth, and means for varying the distance in which the last filed tooth may be positioned beyond the position in which it was filed. 60

4. The structure defined in claim 3 in 65 which the dog is yieldingly held in contact with the guide cam arm and the last filed tooth.

5. In a saw filing machine, a file holder, means for imparting saw filing movement to 70 the file holder, a pair of reversely-acting saw-feeding dogs movable to and from operative positions, a shiftable guide cam arm arranged to cause the operative dog to engage the last filed tooth, and means for 75 operating the dogs to cause the operative one to move the saw and position the last filed tooth a predetermined distance beyond the position in which it was filed.

6. In a saw filing machine, a base having 80 a face plate, a crosshead guide pivoted to the face plate and supported on the base for horizontal swinging movement, a pair of concentric slots in the base on arcs of circles the centers of which are at the axis 85 of the pivotal support for said guide, and bolts working through said slots for securing the crosshead guide to the base in different adjustments.

In testimony whereof I affix my signature.

FREEMAN E. COLLIER.
